UNITED STATES PATENT OFFICE.

BERT B. MILNER, OF NEW YORK, N. Y.

METHOD OF AND APPARATUS FOR ADJUSTING LOCOMOTIVE REVERSING MECHANISM.

1,372,445.

Specification of Letters Patent. Patented Mar. 22, 1921.

Application filed February 20, 1919. Serial No. 278,249.

To all whom it may concern:

Be it known that I, BERT B. MILNER, a citizen of the United States, residing at New York, in the county of New York and State of New York, have invented certain new and useful Improvements in Methods of and Apparatus for Adjusting Locomotive Reversing Mechanism, of which the following is a specification.

10 This invention relates to an improved method of and apparatus for adjusting the reversing mechanism of steam locomotives, for the purpose of developing the maximum power or draw bar pull of the locomotive at different speeds.

15 In steam railroad operation, for example, in starting trains in local passenger service, where many stops must be made and normal running speeds obtained between them as promptly as possible in order to be able to 20 make schedule satisfactorily, it is of great practical importance that the maximum possible draw bar pull be maintained throughout the period of acceleration. As locomotives are being started from a stop, it is necessary to employ a strong, steady pull, beginning at their lowest speeds and hence to set the locomotive valve gear in such 25 manner as to allow the cylinders to take steam throughout all, or throughout most, of the piston stroke. Afterward as the trains approach the desired normal running speeds, it is required in order to prevent an undue back pressure that the cut-off be arranged to occur earlier and earlier in the 30 stroke, and finally as early as practical or consistent with the work to be done. Heretofore, it has been left entirely to the judgment of the engineer, just when and how the valve gear should be shifted during the 35 period of acceleration from start to the normal running speeds and to the final running position of the valve gear, and in controlling this matter economy of operation or 40 steam consumption has been one of the dominating factors. I have found that if economy of steam consumption be disregarded, for each speed of the locomotive there is a particular point of cut-off which 45 will give the highest draw bar pull and, therefore, the highest rate of acceleration to the locomotive and its train, and have devised means of facilitating the practical employment of this information by a corresponding method of operation. The new 50 method involves progressive adjustment of

the cut-off in such a way that it shall always be at (or at least closely approximate) that at which is developed the maximum draw bar pull for the speed existing at each particular stage of the locomotive's progressive acceleration.

55 I accomplish the foregoing result by means of an apparatus illustrated in preferred form in the accompanying drawings, wherein:

Figure 1 illustrates the application of my invention to the standard manually operated reversing mechanism of a locomotive; Fig. 2 illustrates a modification thereof in which the reversing mechanism is automatically shifted to the proper position to obtain the desired cut-off; Fig. 3 shows a modification of my invention in which the reverse lever is automatically shifted to obtain maximum draw bar pull, but which leaves the reverse lever subject also to manual control; Fig. 4 shows a longitudinal section of a cylinder employed in the apparatus of Fig. 3; Fig. 5 is a similar view of a pressure pump forming part of this apparatus; and Fig. 6 shows the corresponding reverse lever arrangement.

Referring particularly to Fig. 1, it will be seen that I have therein illustrated in diagrammatic form a portion of a locomotive A equipped with a standard form of valve motion, such, for example, as the well-known Walschaert gear B, the construction and operation of which are well understood in the art. A reach rod 7 for operating the block 8 of the valve motion is connected in the usual manner to a reverse lever 9, associated with the quadrant diagrammatically indicated at 10. A speed indicator C is mounted in the cab of the locomotive and its operating shaft 11 is driven by any standard form of driving mechanism, such, for example, as the belt 12 driven from the axle 13 of one of the wheels. The speed indicator 14 dial is graduated for a reading of miles per hour, and the quadrant 10 is also correspondingly graduated in miles per hour; that is to say; the positions to which the reverse lever 9 should be cut back to alter the cut-off to obtain maximum draw bar pull at the particular speeds, are indicated in miles per hour. If preferred, the indications of the speed indicator C may be made to read in any selected means of reverse lever position indication, such as the use of corresponding numerals, letters, or the like.

By this arrangement it will be apparent that the engineer, on examination of the dial of the speed indicator, will be apprised of the position to which he should move the 5 reverse lever in order to obtain the maximum draw bar pull at the respective speeds. The advantage of this is, of course, obvious.

The positions to be marked on the quadrant 10 are those which, for the corresponding 10 speeds of the locomotive, will give the maximum draw bar pull. These can best be determined by practical trial. If a dynamometer car is available, it will suffice to run the locomotive at various cut-offs and at 15 the various speeds for which the quadrant 10 is to be graduated, and note, for each speed, from dynamometer car results, the position of the reverse lever for which the draw bar pull is a maximum. If a dynamometer 20 is not available, the calibration can be effected in the following manner:

Attach the locomotive to be calibrated to the front end of a train of some 45 to 50 cars, and run it with a previously selected 25 and fixed cut-off at any desired speed, up a convenient grade, employing another locomotive by which the desired speed is maintained, as a pusher at the rear end of the train. Then note the position of the reverse 30 lever for which the slack coupling between the pulled and the pushed sections of the train occurs farthest back in the train. This will be the position of maximum draw bar pull for the test speed, since in this condition 35 the locomotive being tested is pulling the greatest load. If no speed indicator be available, the speed can be determined from the time required to traverse a measured and marked stretch of track. It is, of course, necessary that the rear locomotive 40 maintain the selected speeds constant over this stretch of track.

In the arrangement shown in Fig. 2, I have shown a means whereby the reverse 45 lever is automatically shifted to the proper position, the valve motion B in this case being operated by a standard form of power reverse mechanism, such, for example, as the well-known Ragonnet power reverse D, the 50 operation of which is well understood.

In this embodiment of my invention the reverse lever 9 is operatively connected to an operating cylinder E by the rod 14. The valve 15, for controlling the admission of 55 operating fluid to the power cylinder E is controlled by a regulator F which has a flexible operating shaft 16 driven in the same manner and preferably by the same means as is the operating shaft 11 of the 60 speed indicator C. It will be apparent that the valve 15 of the power cylinder E will be shifted to admit fluid in accordance with the direction of running. In order to stop the power reverse lever 9 in the proper position, as it is actuated by the power cylinder

E, I provide a second regulator G, also driven by a flexible shaft 17, driven from the belt 12. The regulator G operates to shift the position of a stop 18 carried on the reach rod 7 to correspond to the particular speed of the engine. The reach rod 7 is also provided with a fixed stop or abutment 19.

The operation is as follows: Assuming that the reverse lever has been shifted to 75 full forward position, in order to start the locomotive, as soon as the locomotive reaches successively higher and higher speeds, the regulator F will shift the valve mechanism 80 and admit fluid pressure to the operating cylinder E in such direction as to cut back the power reverse lever to predetermined positions producing maximum possible draw bar pull corresponding to the speeds attained. During this operation the regulator G will shift the stop 18 to assume positions corresponding to the speeds attained, and the power cylinder E will correspondingly shift the power reverse lever 9, as indicated, to points at which the abutment 85 19 comes into engagement with the stop 18. The reverse lever is, therefore, shifted to and held in the proper position to obtain a cut-off in the cylinders adapted to produce the maximum draw bar pull at such 90 speed. As the speed changes, so does the regulator G shift the position of the stop 18 and the power cylinder E shift the reverse lever until movement is again arrested by the engagement of the abutment 19 with 95 the stop 18. When the power reverse D is 100 operated to shift the reverse lever 9 to backward position, the operation of the power cylinder E and regulators F and G is the same as hereinbefore described, but in the 105 reverse manner. The advantage of this arrangement over the first described is that the operation is entirely automatic and the obtaining of the development of maximum draw bar pull at all times cannot be defeated by the negligence of the engineer.

In the arrangement shown by Fig. 3, is illustrated a semi-automatic means of controlling the cut-offs such as is necessary to obtain either maximum draw bar pulls at 110 various speeds or draw bar pulls less than the maximum. In this arrangement, D' is a power reverse gear of standard type. 9' is the reverse lever controlling the reverse gear D'. H is a fluid pressure pump driven 115 from the driving axle of the locomotive 120 discharging to one end of the control cylinder J. The control cylinder is connected to the lower end of a lever 20 mounted on the same pivot as the reverse lever 9'. The upper end 21 of the lever 20 forms an adjustable stop on the front side of the reverse lever. A spring 22 (see Fig. 4) in the opposite end of the control cylinder J, to which the fluid is admitted, holds the lever 125 130

20 and the stop thereon in extreme forward, or full gear, position except when the piston is actuated by pressure of the fluid discharged by the pump H.

5 As the speed of the locomotive increases, the fluid discharged by the pump H exerts a certain pressure on the face of the piston 23 in the control cylinder J causing it to be displaced toward the right. The displacement of the piston causes a corresponding displacement, toward the center, of the limiting stop 21, on the lever 20. The amount of movement desired to obtain the proper cut-off is regulated by by-passing the fluid 10 through the pipe 24, the opening through which is controlled by a restricted orifice in the gasket of pipe union 25.

It will thus be seen that in starting a train, in order to obtain maximum draw bar 20 bull and, therefore, greatest possible acceleration, it will be unnecessary for the engineer to manually adjust the reverse lever as is now necessary, the proper adjustment of the lever being accomplished by the stop 21 25 on the lever 20, which pushes the reverse lever 9' backward as the speed of the locomotive increases.

For the purpose of allowing the lever to be pushed backward by the automatic means, I prefer to make the notches in the reverse 30 lever quadrant V-shaped so that the latch may be forced out of engagement when the lever is actuated by the automatic means.

In case the speed of the locomotive decreases (as when an adverse grade is encountered), it is only necessary, in order to obtain the development of maximum draw bar pull, for the engineer to return the lever to the stop of the automatic means.

40 When less than maximum draw bar pull is required, the reverse lever can be manually adjusted in any desired position to the rear of the adjustable stop.

It will, of course, be understood that 45 my invention has greatest utility during the period of acceleration from starting to normal running speeds, under normal or average load conditions. Under other circumstances the variations in the load conditions 50 may be such that the cut-off indications will not be precisely those at which maximum draw pull is developed. For example, a speed of twenty miles per hour on a level will require a different cut-off adjustment 55 to produce maximum draw bar pull than the same speed up grade. For these reasons, I prefer the constructions of Figs. 1 and 3 for in either, the engineman may manually further manipulate the reverse lever to obtain the desired result, in which connection 60 it is to be observed that in practically all cases where such additional adjustment is required, the cut-off should be shortened over the indicated adjustment.

65 However, during progressive acceleration to normal running speeds, the improvements afford an almost uniformly accurate indication of that cut-off which will produce maximum draw bar pull and therefore maximum efficiency and economy in 70 train operation, even though, temporarily, greatest economy in steam consumption may possibly not be obtained.

I claim:

1. The method of obtaining maximum 75 draw bar pull from a steam locomotive throughout acceleration to normal running speeds which consists in determining, regardless of economy in steam consumption, those cut-offs necessary for the development 80 of desired maximum draw bar pull by automatic means operable upon motion of the locomotive.

2. In a locomotive having a valve motion, a reverse lever and a reverse lever 85 quadrant, the combination of a speed indicator graduated to indicate the speed of the locomotive and corresponding gradations on the quadrant.

3. The combination with a locomotive 90 having a valve motion and reversing mechanism controlling the same, of means under the control of engine speed for automatically actuating the reversing mechanism to alter the degree of cylinder cut-off to correspond with the speed of the locomotive.

4. The combination in a locomotive having a valve motion and a reverse means for operating the same, of power operated 100 means for shifting said reverse means, and means under the control of the speed of the engine for actuating said operating means.

5. In a locomotive having a valve motion and a reverse lever for operating the same, 105 a power cylinder for shifting the reverse lever and a regulator for controlling the admission of operating fluid to said power cylinder coupled to a rotating portion of the locomotive.

6. The combination in a locomotive having a valve motion and a reversing mechanism for operating the same, of a power cylinder for shifting said reversing mechanism, a regulator for controlling the admission of operating fluid to said cylinder, 115 and driving mechanism for said regulator coupled to an axle of the locomotive.

7. The combination in a locomotive having a valve motion and a reverse means for 120 operating the same, of power means for shifting said reverse means, means for limiting the movement of said reverse means, and means actuated by the speed of the locomotive for determining the operation of 125 said limiting means.

8. The combination in a locomotive having a valve motion and a reverse lever for operating the same, of a power means for shifting said reverse lever, a variable stop 130

- means for limiting the movement of the reverse lever, and a speed controlled regulator for determining the position of said stop means.
5. 9. The combination in a locomotive having a valve motion and a reverse mechanism for operating the same, of a speed controlled power means for shifting said reverse mechanism, and a speed controlled means for 10 limiting the movement of the reverse mechanism.
10. The combination in a locomotive having a valve motion and a reverse mechanism for operating the same, of speed controlled 15 means for limiting the movement of the reverse mechanism.
11. In a locomotive having a valve motion, the combination therewith of means responsive to the locomotive speed for automatically determining the point of cut-off 20 for maximum draw-bar pull at any speed.
12. In a locomotive the combination of a reverse lever, a cut-off indicator mechanism adjacent the lever, and a medium for operating the indicator mechanism operable 25 on motion of the locomotive.
13. In a locomotive the combination of a reverse lever, means for shifting the lever to alter the cut-off and an automatic medium for operating said means on motion of the locomotive.
14. In a locomotive having a valve motion, a reverse lever and a reverse lever quadrant, the combination of a cut-off indicator, means operating the same on motion 35 of the locomotive, said quadrant having corresponding graduations.
15. The herein described method of obtaining maximum draw bar pull which consists in automatically adjusting the cut-off 40 proportionately to the speed of the locomotive, but with additional adjustment subject to manual control.

In testimony whereof, I have hereunto signed my name.

BERT B. MILNER.
